UNITED STATES PATENT OFFICE.

LAWRENCE ADAMS, OF LAYTON, UTAH.

COMBINED BEET-HARVESTER.

1,390,261.

Specification of Letters Patent. Patented Sept. 13, 1921.

Application filed June 24, 1920. Serial No. 391,309.

To all whom it may concern:

Be it known that I, LAWRENCE ADAMS, a citizen of the United States, residing at Layton, in the county of Davis and State of Utah, have invented a new and useful Combined Beet-Harvester, of which the following is a specification.

This invention relates to a machine for harvesting and topping beets, one of its objects being to provide a machine of this character which can be drawn or otherwise propelled along a row of beets and will successively dig the beets, convey them upwardly, remove the tops, and then deliver the tops and the beets separately from the machine.

A further object is to provide novel means for engaging the beets and conveying them to the topping mechanism.

Another object is to provide novel means for gripping the beets during the topping operation and subsequently delivering said beets from the machine.

Another object is to provide a laterally extending beet conveyer for discharging beets from the machine, said conveyer having mechanism whereby it can be adjusted longitudinally relative to the machine without interfering with the operation of the conveyer.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings

Figure 1 is a plan view of the machine.

Fig. 2 is a side elevation.

Fig. 3 is a rear end elevation.

Fig. 4 is a bottom plan view.

Fig. 5 is a section through one of the topping disks and showing adjacent parts.

Referring to the figures by characters of reference 1 designates an elongated frame the rear portion of which is supported by wheels 2 engaging the ends of an axle 3. Bearings 4 are provided at the sides of the front portion of this frame and extending through them are spindles 6 mounted for

longitudinal sliding movement and also mounted for rotation in and movement with a cross head 7 extending under the front portion of the frame 1. A bell crank lever 8 is fulcrumed on the frame and one end thereof is connected by a link 9 to the cross head 7 while the other end of the lever has an operating rod 10 extending rearwardly to a point adjacent a seat 11 adapted to be occupied by the driver, this seat being arranged at the rear end of the machine. A rack 12 is arranged adjacent lever 8 and is adapted to be engaged by a dog indicated generally at 13 and which is operated by a wire or the like, 14, extending through a small hand lever 15.

Each of the spindles 6 has a forked lower end 16 in which is journaled a wheel 17 and a crank arm 17¹ is extended inwardly from the upper end of each spindle. These crank arms have rods 18 connected to them and extending rearwardly to a foot lever 19 located in front of the seat 11 and adapted to be operated by the occupant of the seat. Thus it will be seen that by manipulating this foot lever the machine can be steered and by means of the rod 10 the front end of the machine can be raised or lowered.

Guide brackets 20 are provided at the sides of the frame 1 and back of the brackets 4 and in each of them is slidably mounted a stem 21 having a head 22. The two heads are connected by a cross shaft 23 and a spring 24 is mounted on each stem 21 and serves to hold the head 22 pressed downwardly. Hangers 25 are fixed to the sides of the frame 1 and have links 26 pivoted to them, and to the heads 22, thus to reinforce the stems. The bearings 20 are pivotally connected to the sides of the frame 1 by bolts 27 so as to be free to swing slightly during the up and down movement of the stems 21.

Extending from the sides of the frame 1 are standards 28 and secured to the lower end of each standard is a digging plow 29, the two plows being so shaped and positioned relative to each other as to work under the beets in the soil and elevate them.

A roller 30 is mounted on the shaft 23 and supports the front portion of an upwardly and rearwardly inclined endless conveyer 31 the upper portion of which is mounted on a roller 32 carried by a transverse shaft 33. Longitudinal series of outwardly extending spikes are secured to the belt or conveyor 31,

as shown at 34 and are adapted successively to move into position between the plows 29 and in the direction indicated by the arrow in Fig. 2.

- 5 The rear portions of the sides of the frame 1 are preferably dropped below the level of the upper portion of the conveyer 31 and provide bearings for opposed vertical rollers 35 each of which has a bevel gear 36 secured to the lower end thereof and rotat-
10 ing therewith. Gears 37 mesh with the gears 36 and are secured to short laterally extending shafts 38 journaled in brackets 39 and sprockets 40 on the shafts 38 receive motion
15 through chains 41 from sprockets 42 secured to the shaft 33.
- Mounted on the rollers 35 are endless gripping belts 43 which extend into engagement with suitably arranged guide rollers
20 44 and also into engagement with pressing rollers 45 arranged in pairs. Each of these rollers 45 is carried by a pivoted arm 46 yieldingly pressed inwardly by a spring 47. These rollers 45 engage the inner portions
25 of the two endless gripping belts and the arms 46 are so proportioned and located as to hold the belts so as to form a throat or contracted passage as indicated in Fig. 4. Back of this throat is arranged a delivering
30 spout 48 which extends downwardly from a point above the throat, the bottom of this spout constituting means for deflecting downwardly beets gripped between the belts as hereinafter pointed out. Arranged
35 transversely under the rear end of the throat formed by the belts 43 and below the upper end of the spout 48 is a transverse conveyer 49 which is slidably mounted in the frame 1 or, more particularly, in a de-
40 pending extension 50 upon the rear portion of said frame, as shown in Fig. 2. A rack 51 is formed longitudinally on the bottom of the frame 52 of the conveyer 49 and is constantly in mesh with a gear 53 journaled in a bearing 54 fixed to the frame 1. A sprocket 55 rotates with this gear and is adapted to be actuated by a chain 56 extending upwardly to a sprocket 57 secured to a small crank shaft 58. This shaft is journaled in a standard 59 adjacent the seat 11 and, by rotating the crank 60 on the shaft 58 the gear 53 can be rotated so as to shift the conveyer 49 longitudinally with its delivery end any desired distance from the side of the frame 1. The endless belt forming the conveying portion of the conveyer 49 is mounted on rollers 61 one of which is provided with a gear 62 constantly meshing with another gear 63 on a shaft 64 extending longitudinally of the frame 52. This shaft 64 is feathered in a sprocket 65 adapted to receive motion through a chain 66 from another sprocket 67 loosely mounted on the rear axle 3. By means of a clutch 68
65 under the control of the driver the sprocket

67 can be locked to or released from the axle 3 so as to control the transmission of power from said axle to the shaft 64 and, consequently, control the actuation of the conveyer 49.

70 Supported in the frame 1 and above the belts 43 are vertical shafts 69 each of which is provided, at its lower end, with a top-
75 ping disk 70, the inner portions of the two disks lapping as shown. Gears 71 are se-
cured to the upper ends of the shafts 69 and mesh with gears 72 secured to transverse shafts 73. Each of these shafts has a sprocket 74 secured to its outer end and adapted to receive motion through a chain 80
75 from a sprocket 76 secured to the shaft 33.

76 Each of the vertical shafts 69 has a collar 77 slidable on it and carrying the disk 70. The collars are mounted for rotation in the ends of a bowed stop strip 78 and se-
85 cured to the end portions of this stop strip are arms 79 extending downwardly from the ends of a cross bar 80. This cross bar is engaged by a lifting arm 81 extending forwardly from a hand lever 82 adapted to be operated by the driver and having any suitable means, such as a rack 83 for en-
86 gagement by a pawl or dog (not shown) of the usual construction. A deflecting strip 84 is mounted in the frame 1 adjacent the 95 uppermost portion of the elevator 31 and constitutes means for stripping beets from the spikes or prongs 34 as they are brought into position at the front end of the throat between the belts 43. This cross strip 84 100 has recesses through which the spikes 34 will pass.

96 The machine herein described can be drawn forward by a team of horses or can be propelled by a tractor or by its own 105 power. The spikes 34 will dig into the soil and enter the beets in the paths thereof and which beets have been loosened by the plows 29. This action will cause the conveyer or elevator 31 to operate by reason of its roll-
110 ing contact with the ground and such operation will not only result in the elevation of the spiked beets with their tops uppermost but will also result in the transmission of motion from the conveyer or elevator 31 115 to the shaft 33 and the various parts driven thereby. Thus the beets will be received between the belts 43 and be yieldingly gripped by them, so that the beets will be forcibly pressed against the disks 70. As these disks 120 are rotated the tops of the beets will be sev-
125 ered thereby and will be directed rear-
wardly against the stop strip 78 which will cause them to drop onto the delivery spout 48. The beets from which the tops have been removed will subsequently enter the widened rear portion of the throat between the belts 43 and will be released, dropping to the side delivery conveyer 49. By means of the lever 82 the disks 70 can be raised or 130

lowered so as to properly adjust them to the tops to be severed.

What is claimed is:

1. A machine of the class described including a portable structure, an upwardly and rearwardly extending conveying belt, outwardly projecting beet engaging spikes upon the belt for entering the soil and actuating the belt, and means operated by said belt for gripping the elevated beets and removing them from the belt.

2. The combination with a movably supported structure, of an upwardly extending conveying belt, beet engaging spikes extending therefrom for entering the soil and actuating the belt during the movement of the machine, opposed belts for receiving elevated beets therebetween, means for transmitting motion to said opposed belts from the conveying belt.

3. The combination with a movably supported structure, of an upwardly extending conveying belt, beet engaging spikes extending therefrom for entering the soil and actuating the belt during the movement of the machine, opposed belts for receiving elevated beets therebetween, means for transmitting motion to said opposed belts from the conveying belt, said opposed belts forming a throat therebetween, and means for yieldingly pressing the opposed belts against beets within the throat to convey said beets away from the conveying belt.

4. The combination with a movably supported structure, of an upwardly extending conveying belt, beet engaging spikes extending therefrom for entering the soil and actuating the belt during the movement of the machine, opposed belts for receiving elevated beets therebetween, means for transmitting motion to said opposed belts from the conveying belt, topping means supported above said opposed belts, and means for transmitting motion to said topping means from the conveying belt.

5. The combination with a movably supported structure, of an upwardly extending conveying belt, beet engaging spikes extending therefrom for entering the soil and actuating the belt during the movement of the machine, opposed belts for receiving elevated beets therebetween, means for transmitting motion to said opposed belts from the conveying belt, topping means supported above said opposed belts, and means for transmitting motion to said topping means from the conveying belt, and means for raising and lowering the topping means relative to the belts during the actuation of said topping means.

6. The combination with a movable structure and beet engaging and elevating means operated by contact with the ground, of opposed gripping belts for engaging elevated beets and conducting them away from said elevating means, topping means above the gripping belts, and mechanism operated by the beet elevating means for driving the gripping belts and the topping means.

7. The combination with a movable structure and beet engaging and elevating means carried thereby and actuated by contact with the ground, of opposed gripping belts forming a throat therebetween for receiving the elevated beets and conveying them from the elevating means, a conveyer extending under the gripping belts, said throat having a widened portion above the conveyer thereunder for releasing the gripped beets to deliver them to said conveyer.

8. The combination with a movable structure and endless beet engaging and conveying means carried thereby and operated by contact with the ground, of opposed beet gripping belts forming a throat therebetween, topping mechanism above the belts, a delivering conveyer below the belts, said throat being widened above the delivering conveyer to release beets therethrough, an outlet spout extending under the topping means, and means for stopping the severed tops and delivering them to the spout.

9. The combination with a movable structure, of beet engaging and elevating means operated by contact with the ground, opposed gripping belts forming a throat therebetween for the reception of elevated beets, said belts forming a throat therebetween having a widened portion, a delivering conveyer under the widened portion of the throat, means operated by the movement of said structure for actuating the delivering conveyer, and means under the control of the operator for shifting the delivering conveyer bodily during the actuation thereof.

10. The combination with a portable structure and digging means carried thereby, of an upwardly extending endless conveyer, and beet engaging spikes projecting from the conveyer and movable successively by contact with the ground to engage and elevate beets loosened by the digging means.

In testimony that I claim the foregoing as my own, I have hereto affixed my signature in the presence of two witnesses.

LAWRENCE ADAMS.
